UNITED STATES PATENT OFFICE

ANDREW R. KERR, OF GREAT FALLS, MONTANA

TOOL

Application filed May 22, 1931. Serial No. 539,326.

This invention relates to tools especially adapted for applying couplings to bendable tubes or pipes, and more particularly to a device for flaring the end of a tube to form a flange for engagement with the seat within a coupling so that a leak-proof connection will be had between the tube and coupling when the latter is threaded to its companion section or nipple.

10 Another object of this invention is the provision of a screw-threaded shank adapted for threaded engagement with the coupling and carrying means for flaring the end of the tube against the seat of the coupling when rotated relative to the tube and by having the shank threaded to the coupling to permit said shank to be adjusted relative to the coupling for increasing the action of said means on the end of the tube as desired.

20 A further object of this invention is the provision of a tool of the above stated character which will be simple, durable and efficient and which may be manufactured and sold at a comparatively low cost.

25 With these and other objects in view, this invention consists in certain novel features of construction, combination and arrangement of parts to be hereinafter more fully described and claimed.

30 For a complete understanding of my invention, reference is to be had to the following description and accompanying drawing, in which

35 Figure 1 is a side elevation illustrating a tool applied to a coupling and bendable tube and constructed in accordance with my invention,

40 Figure 2 is a sectional view illustrating the application of the tool to the coupling prior to flaring the end of the tube,

45 Figure 3 is a similar view showing the end of the tube flared by the tool,

Figure 4 is a side elevation illustrating the tool removed from the coupling,

45 Figure 5 is an end elevation illustrating the means on the shank for flaring the end of the tube when the shank is rotated relative to said tube,

50 Figure 6 is a side elevation illustrating the tube prior to being flared, and

Figure 7 is a similar view showing the tube after being flared.

Referring in detail to the drawing, the numeral 1 indicates a bendable tube with a coupling 2 associated therewith, and the latter includes a body 3 with a comparatively long neck 4 of a diameter less than the diameter of the body and which snugly fits the tube 1 with one end of the tube extending into the body. Due to the difference in the diameters of the body and neck, a tapered seat 5 is formed within the body, and the interior of the body from the seat 5 to the free end of the body is screw-threaded as shown at 6. The foregoing description relates to a well-known type of coupling adapted to be secured to the tube by flaring the end of the tube against the seat 5 as shown in Figure 3 so that when the coupling is threaded to its companion section or nipple (not shown), the flared end of the tube will tightly fit the seat and thereby establish a leak-proof connection. To easily and quickly flare the end of the tube so as to evenly fit the seat 5, my tool is provided, and it is to be understood that my tool may be constructed in various sizes so as to fit the different sized couplings now on the market.

55 A screw-threaded shank 7 has formed upon one end a head 8 provided with an opening therethrough to slidably receive a bar 9 having headed ends 10 to prevent separation of the bar from the head but which will permit the bar to be adjusted relative to the head for the purpose of increasing and decreasing the leverage at one side of the head as desired, it being understood that the bar acts as a medium for a person to turn the shank.

60 The other end of the shank has formed eccentrically thereof a semi-conical shaped flaring element 11 providing an arcuately curved flaring face 12 for engagement with the end of the tube as shown in Figure 2. The apex or smallest end of the flaring element 11 enters the tube first when the shank is applied to the coupling as shown in Figure 2. The shank is threaded into the coupling until the flaring element 11 is brought into engagement with the end of the tube with sufficient force to cause flaring of the end of

the tube when the shank is rotated relative to the tube. As the flaring of the tube takes place, the shank may be adjusted relative to the coupling by holding said coupling and turning the shank relative thereto, so that when the final bending or flaring of the end of the tube takes place, it will snugly fit or conform to the seat 5 of the coupling.

From the foregoing description taken in connection with the accompanying drawing it will be noted that a tool constructed in accordance with my invention will permit a tube when in an installed position to be easily flared against the seat of a coupling without removing the tube, thereby rendering the device very advantageous to mend copper tubing and the like employed upon motor vehicles and other machinery or wherever bendable tubing is employed.

While I have shown and described the preferred embodiment of my invention, it will be understood that minor changes may be made in the construction, combination and arrangement of parts without departing from the spirit and scope of my invention as claimed.

Having thus described my invention, what I claim is:

In combination with a tube coupling having a flared seat, a screw-threaded shank threaded in the coupling, means for rotating the shank, and a semi-conical shaped element formed eccentrically with one end of the shank with the smallest end thereof spaced from the end of the shank and adapted to extend into the end of a tube with the curved wall of said element engaging the wall of the tube adjacent the end of the latter and during the rotation of the shank adapted to gradually flare said wall of the tube tightly against the flared seat of the coupling without breaking or cracking the tube.

In testimony whereof I affix my signature.

ANDREW R. KERR.
